(57) **CLAIM**

The ornamental design for a household tool and appliance holder, as shown and described.

DESCRIPTION

FIG. 1 is a front elevation a house hold tool and appliance holder (hereafter "the holder") showing my design;
FIG. 2 is a back elevation of the holder of FIG. 1;
FIG. 3 is a right side elevation of the holder of FIG. 1. A left side elevation view (not illustrated) of the holder of FIG. 1 is a mirror image of the right side elevation shown in FIG. 3;
FIG. 4 is a top elevation of the holder of FIG. 1;
FIG. 5 is a bottom elevation of the holder of FIG. 1; and,
FIG. 6 is a perspective view of the holder of FIGS. 1-5 and shown in a position of use hanging flexibly over the edge of a table. The broken lines showing the edge of the table in FIG. 6 are for illustrative purposes only and form no part of the claimed design.
